UNITED STATES PATENT OFFICE.

DAMIAN JOKUBAITIS, OF TERRE HAUTE, INDIANA.

STARTER FOR AUTOMOBILES.

1,349,207.

Specification of Letters Patent. Patented Aug. 10, 1920.

Application filed October 15, 1919. Serial No. 330,707.

To all whom it may concern:

Be it known that I, DAMIAN JOKUBAITIS, a citizen of Russia, residing at Terre Haute, county of Vigo, and State of Indiana, have 5 invented certain new and useful Improvements in Starters for Automobiles, of which the following is a specification.

The principal object of this invention is to provide means for electro-mechanically 10 starting an automobile.

Another object is in the provisions made for mechanically transmitting rotary motion, through a spring actuated mechanism, to the distributor system.

15 These objects are attained by the novel construction of parts hereinafter described and shown in the accompanying drawings, forming a material part of this disclosure, and in which—

20 Figure 1 is a top plan view showing the relation of unit parts.

Fig. 2 is a side elevational view taken on line 3—3 of Fig. 4.

Fig. 3 is a sectional view taken on line 25 3—3 of Fig. 4.

Fig. 4 is a front elevational view, partially broken away to show interior parts, and

30 Fig. 5 is a sectional view taken on line 5—5 of Fig. 4.

Referring to the drawings in detail, the numeral 10 designates the starter box or casing, mechanically connected to a distributor 11, having electrical connection with a 35 battery 12, a spark coil 13, the spark plugs 14 and engine cylinders 15.

Rotatably mounted in the casing 10 and the removable cover 16, is a shaft 17 extending outwardly and having fixedly attached 40 a spur gear 18 secured to a shaft journaled in the cover 16 and the gear case 20, the shaft having a crank 21 removably attached at the end provided with a handle 22 for turning.

45 An annular spring drum 23 concentrically and fixedly attached to the outer side of the spur driving gear 24, adjacent to the inner side of the cover 20, contains a flat spiral operating spring 25, having its outer extremity fixed to the drum 23 by the rivet 26, and its inner end attached to the shaft 17 by the hook element 27.

A spur gear 24 is freely rotatable upon the shaft 17 and has formed upon the outer

section of its inner side, a series of radially 55 cut detent teeth 30.

A ratchet 31 is secured to the shaft 17, engageable with the spring controlled pawl 32 pivotally attached to the gear 24. A sprocket gear 33 is rotatably held between 60 the shoulder 34 of the shaft 17 and a ratchet 35 fixed to the shaft 17, and is engageable with the spring controlled pawl 36 pivotally attached to the sprocket gear 33.

A bracket 37, fastened upon the casing 10 65 and extending inwardly, is provided with a bearing for one end of the shaft 38, the other extremity of which is mounted within a bearing in the case 10. Secured to the shaft 38 is a spur gear 40 and the small 70 sprocket gear 41, driven by the large sprocket 33 by means of the chain 42.

A shaft 43, extending through the casing 10 and rotatably journaled therein, and also in the cover 16, has secured upon it the long 75 pinion 44 which meshes with the gears 24 and 40.

A locking lever 45 is pivoted within a slot provided in a lug 46, integral with the casing 10, this lever 45 having upon its free 80 offset end a series of detent teeth 47 engaging similar teeth in the gear 24 the same being connected by an operating rod 48 attached to the lever, and passing through the cover 16 where it is normally held in an 85 engaged position by the coiled spring 49 and released by pulling the handle 50 outwardly.

In operation, the spring operated mechanical starter is attached to the dash board of 90 an automobile and has means provided for transmitting a rotary motion from the shaft 43 to the distributor 11, this means not being a part of this invention. The winding of the operating spring is accomplished by 95 turning the crank handle, transmitting rotary motion through a simple train of gears to the spring shaft and winding thereon the operating spring, the outer end of which is secured to a casing, which in 100 turn is attached to a spur gear rotatable upon the spring shaft, but retained or locked by the detent lever engaging with the radial teeth formed upon the side of the spur gear, thereby preventing the gear from 105 turning.

An outward pull on the lever handle disengages the detent and allows the gear, ener-

gized by the spring, to rotate upon the shaft and mesh with the long pinion, causing the pinion and its shaft to rotate. The shaft is connected to the rotating element within 5 a rotary distributor having contact elements provided for an electric current generated in the battery and passing through the spark coil and by wires connecting the distributor with the spark plugs, causing a properly 10 timed spark to take place within the explosion chamber of the motor cylinders.

A sprocket and chain drives the smaller sprocket secured to the shaft and having a spur gear in mesh with the long pinion, 15 is free to revolve around its shaft in one direction but held from turning in the opposite direction by a ratchet and engaging pawl attached to the sprocket gear.

Another similar ratchet is secured to the 20 spring shaft, adjacent to the driving gear, and prevented from turning except in one direction by a pawl attached to the driving gear. By means of these ratchets and pawls, and the turning effect derived from the long 25 pinion, the operating spring is constantly rewound.

Having thus described my invention, what I claim as new and desire to secure by Letters Patent, is—

In an automobile starting device of the 30 character described, the combination of an operating spring and its drum carrying a spur driving gear, with a pivotally arranged locking lever, a series of detent teeth on the free end of said lever engaging the teeth 35 of said gear, an operating rod attached to said lever, a spring coiled around said rod for holding the teeth of its detent normally in engagement with the teeth of said gear, and an operating handle adapted to disengage the teeth of said detent and gear upon a pull exerted on said handle, and a long pinion in mesh with said gear adapted 40 to be rotated upon the operation of said locking lever to disengage the teeth of said 45 detent and gear, said long pinion adapted to start the ignition of the machine, substantially as described and for the purpose set forth.

In testimony whereof I have affixed my 50 signature.

DAMIAN JOKUBAITIS.
